DESIGN FOR A CAMERA CARRYING CASE

Frederic S. Grover, Rochester, N. Y., assignor to
The Folmer Graflex Corporation, Rochester,
N. Y., a corporation of Delaware

Application April 1, 1943, Serial No. 109,881

Term of patent 7 years

To all whom it may concern:

Be it known that I, Frederic S. Grover, a citizen of the United States and a resident of Rochester, in the county of Monroe and State of New York, have invented a new, original, and ornamental Design for a Camera Carrying Case, of which the following is a specification, reference being had to the accompanying drawing, forming part thereof.

The figure is a front perspective view of a camera carrying case showing my new design, the parts not shown being plain.

I claim:

The ornamental design for a camera carrying case, substantially as shown and described.

FREDERIC S. GROVER.
